Primary Examiner — Ian Simmons*Assistant Examiner* — Mark Cavanna(57) **CLAIM**

The ornamental design for a cross, as shown and described.

DESCRIPTION

FIG. 1 is an isometric view of a cross showing my new design. The cross is an item of jewelry.

FIG. 2 is a front elevation view thereof, with the rear elevation view being a mirror image thereof.

FIG. 3 is a right side elevation view thereof with the left side elevation view being a mirror image thereof.

FIG. 4 is a top plan view thereof; and,

FIG. 5 is a bottom plan view thereof.

The broken lines shown in the Figures depict environmental subject matter only and are not part of the claimed design.

1 Claim, 1 Drawing Sheet(56)
